Primary Examiner — Cynthia Ramirez*Assistant Examiner* — L. Martinez-Rivera(74) *Attorney, Agent, or Firm* — Seed IP Law Group LLP(57) **CLAIM**

The ornamental design for a butt joint flashing sheet, as shown and described.

DESCRIPTION

FIG. 1 is a front, top, right side isometric view of a butt joint flashing sheet showing my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The broken lines shown in the figures are included for the purpose of illustrating portions of the butt joint flashing sheet that form no part of the claimed design.

1 Claim, 5 Drawing Sheets---
